UNITED STATES PATENT OFFICE.

HOWARD Y. HODGE, OF ELK VIEW, PENNSYLVANIA, ASSIGNOR TO DIXIE VENTILATOR COMPANY, INC., OF KENNETT SQUARE, PENNSYLVANIA, A CORPORATION OF DELAWARE.

VENTILATOR.

Application filed October 6, 1927. Serial No. 224,320.

My invention relates to ventilators of the type adapted to be installed in windows and other openings and has for its principal object to provide a ventilator of this type which is adjustable as to length so that it may be adapted to openings of various sizes.

Another object of the invention is to provide a ventilator which will not obstruct the light entering the room and which may also exclude a large amount of dust and dirt.

These and various other objects and advantages will be apparent from the following description, to be read in conjunction with the accompanying drawings in which

15 Figure 1 is a perspective view of a ventilator embodying my invention, as same would appear when mounted on a window.

Figure 2 is a perspective view of one of the ventilator sections shown in Figure 1 but 20 viewing same from the opposite side; certain parts being broken away.

Figure 3 is an elevation of the ventilator shown in Figure 1 but viewing same from the opposite side.

25 Figure 4 is a transverse sectional view, taken on line 4-4 on Figure 3.

Figure 5 a similar view taken on line 5-5 on Figure 3, and

30 Figure 6 a fragmentary sectional plan view taken on line 6-6 on Figure 4.

The embodiment shown in the drawings is provided with a pair of rigid end pieces 11 and 11^a which are opposite hand to one another and provided with upwardly extending ears 12 having apertures 13 by means of which the ventilator may be swingably mounted in a window casing, as by screws 14, preferably with the edge 15 of each end piece in close proximity to the side rails of the bottom sash and the curvature of the tops of ears 12 should be such that the ventilator may be swung on screws 14, if so desired.

35 The body parts of the end pieces are substantially triangular and a guide 16 has one end secured to the end piece 11 at the apex of the triangle and overlaps a guide 16^a similarly secured to end piece 11^a. The two guides are held in sliding engagement with one another by a pair of casings 17 which are preferably made of thin metal and shaped as shown in Figures 4 and 5. The outstanding portions of guides 16 and 16^a are reduced in thickness to form auxil-

iary guides 18 and 18^a, respectively, whose 55 combined thicknesses are approximately equal to the thickness of a guide proper. Auxiliary guide 18 overlaps auxiliary guide 18^a so that, with the assistance of casings 17, these auxiliary guides allow the ventilator to 60 be lengthened.

A deflector plate 19 is secured in a suitable groove formed in end piece 11 and in a groove formed in the under side of guide 16 and is adapted to overlap and slidably engage a similar deflector plate 19^a similarly secured in end piece 11^a and in guide 16^a; auxiliary guide 18^a being provided with a groove 65 20 at least twice the width of the groove in guide 16^a so that it may accommodate both 70 of the deflector plates, as shown in Figure 5. Deflector plates 19 may be of any suitable material but have been shown as being glass plates in order that the ventilator will not obstruct the entrance of light to the 75 room.

The upper side of auxiliary guide 18^a is cut away to form a track 21 and the under side of auxiliary guide 18 is cut away to form a similar track for accommodating a portion of one edge of a pair of screens 22 and 22^a. Screen 22^a may be secured to end piece 11^a in any suitable manner but has been shown as having its end secured in a groove formed therein by means of a 80 wedge 23 and has a portion of its side fixed in guide 16^a in a suitable groove which forms the extension of track 21. Screen 22 is similarly secured to end piece 11 and guide 16 so that, when the two ventilator sections are 85 assembled, the free ends of screens 22 and 22^a are held in sliding engagement with one another between auxiliary guides 18 and 18^a while deflector plates 19 are held in sliding engagement with one another by having one 90 edge of each slidably mounted in groove 20. 95

In order that the unconfined corners of screens 22 and 22^a may not sag below the normal plane of the screens, I preferably provide a clip 24 on each corner in order to hold 100 it in sliding contact with its companion screen. Casings 17 have been shown of a length to abut one another when the ventilator is collapsed to its shortest length but this was done for illustrative purposes only 105 and in order to expose auxiliary guides 18 and 18^a as these casings may readily be made to overlap one another approximately the

same distance as screens 22 and 22^a and plates 18 and 19^a overlap one another so that the ventilator will have a finished appearance when extended to fit any size of window within its range.

With my improved ventilator installed in a window, fresh air may be admitted to the room without danger of its blowing directly upon an occupant of the room as it must first strike deflector plates 19 and be deflected upwardly toward the ceiling, where it tends to mix with the warmer air of the room.

Screens 14 may be employed or not, as desired, and may be of any size mesh so that, if a very fine screen cloth is employed, practically no dust or dirt can enter the room through the ventilator. Heretofore, it has been necessary to build ventilators especially for each window but my improved ventilator may be made in standard sizes so that it may be quickly and easily mounted on any size window within its range and thus provide a ventilator at a fraction of the cost of one made especially for a window and it is also found that but two sizes of these ventilators are necessary to fit practically all sizes of windows ordinarily encountered.

While I have illustrated and described an embodiment of my invention and shown a practical application thereof, it is to be understood that modifications may be made without departing from the spirit of the invention, and hence I do not wish to limit myself to the construction set forth, but consider that I am at liberty to make such changes, alterations and applications as fairly come within the scope of the appended claims.

40 I claim:—

1. A ventilator of the character described including end pieces, deflector plates carried by the end pieces, and means secured to the end pieces and one edge of the deflector plates for holding the plates in sliding engagement with one another.

2. A ventilator including end pieces, a guide on each end piece, a deflector plate secured to each end piece and guide, and means holding the guides in sliding engagement with one another.

3. A ventilator including end pieces, a guide on each end piece, a deflector plate secured to each end piece and guide, a screen secured to each end piece and guide, and means holding the guides in sliding engagement with one another.

4. In combination with a window frame, a ventilator including end pieces, deflector plates fixed to the end pieces, means for adjusting the ventilator to different sizes of openings, and means for swingably mounting a ventilator in the window frame.

5. A ventilator including a pair of end pieces, a guide secured to each end piece, auxiliary guides formed on the guides and overlapping one another, a pair of deflector plates secured in the end pieces and guides and slidable in one of the auxiliary guides, screens secured in the end pieces and guides and slidable between the auxiliary guides, and means holding the auxiliary guides in sliding engagement with one another.

6. A ventilator including a pair of end pieces, ears on the end pieces for swingably mounting the ventilator on the sides of an opening, a guide secured to each end piece, auxiliary guides formed on the guides and overlapping one another, a pair of deflector plates secured in the end pieces and guides and slidable in one of the auxiliary guides, screens secured in the end pieces and guides and slidable between the auxiliary guides, and casings on the guides for holding the auxiliary guides in sliding engagement with one another.

7. A ventilator including a pair of end pieces; a guide secured to each end piece; a pair of deflector plates secured to the end pieces and guides and slidable in one of the guides; screens secured in the end pieces and guides and slidable between the guides, and means holding the guides in sliding engagement with each other.

8. A ventilator including a pair of end pieces, grooved guides secured to the end pieces and overlapping each other, a deflector plate secured to each end piece and guide, and slidable in the groove in the other guide, and means for holding the guides in sliding engagement with one another.

9. A ventilator including a pair of end pieces, grooved guides secured to the end pieces and overlapping each other, a deflector plate secured to each end piece and guide, and slidable in the groove in the other guide, and a casing secured to each guide and partially encircling a part of the overlapped portions of both guides.

In testimony whereof I have signed my name to this specification.

HOWARD Y. HODGE.
